LETOFF DEVICE FOR TEXTILE MACHINES

Wilfred Lord, Keighley, England

Application April 28, 1948, Serial No. 23,835
In Great Britain April 9, 1947

9 Claims. (Cl. 139—108)

1

This invention relates to let-off devices for textile machines, and has particular reference to devices for opposing and/or for effecting the rotation of a drum or spindle, off which and/or on to which a thread or the like is being wound, in order to tension correctly the said thread or the like.

In order that the invention may be the more clearly understood, a let-off device in accordance therewith will now be described, reference being made to the accompanying drawings. This device embodies the invention as applied to a textile machine such as a loom, for the purpose of both retarding the drum (known as warp beam) while thread is being wound off it, in such a way as to maintain the tension of said thread constant, and also of effecting the rotation of said drum for re-winding said thread, in such a way as to maintain the tension of the thread constant. In the said drawings:

Figure 1 is a side elevation of the relevant portion of the loom with some of the parts omitted;

Figure 2 is a view to a larger scale of a portion of Figure 1 shown partly in section and with the said parts in place;

Figure 3 is an end elevation viewed from the left of Figure 2 and shown partly in section;

Figure 4 is a section on line IV—IV of Figure 1;

Figure 5 is a section on line V—V of Figure 1;

Figure 6 is a view of a portion of Figure 1 shown at a different operative position.

Referring to the drawings the reference numeral 1 designates the warp beam and the reference numeral 2 the thread. A main lever 3 is provided which rotates about the axis of a horizontal shaft 4 which is parallel to the axis of the warp beam 1. This lever carries a weight 5, and, as will be hereinafter more particularly described, the lever and the warp beam are coupled together by a transmission gear train so that the moment of the lever and weight about its axis applies tension to the thread. Moreover this transmission gear train includes in it a differential gear train 6 and means are provided for automatically adjusting said differential gear in such a way that the lever 3 is maintained within limits always at a normal position fairly close to the horizontal. Thus, when the thread 2 is being drawn off the warp beam 1 the rotation of the warp beam will tend to rotate the lever 3 upwardly in opposition to its gravity bias, but the differential gear 6 will automatically be operated to maintain said lever at its normal position.

2

Thus the tension of the unwinding thread 2 will depend on the gravity bias of the lever 3, but the latter will remain approximately stationary.

In like manner when it is desired to rewind some of the thread 2 on to the warp beam 1, the thread is paid back to the warp beam and the latter will rotate, under the gravity bias of the lever, in the direction for rewinding the thread. The lever will tend to rotate downwardly under its gravity bias, but again the differential gear will be operated to maintain said lever at its normal position. Thus the tension of the winding thread will depend on the gravity bias of the lever, but the latter will remain approximately stationary.

Finally the position of the weight 5 along said main lever 3 is varied according to variations of the radius at which the thread 2 is wound off or onto the warp beam 1, in such a direction that it approaches the axis of the lever as the said radius diminishes, and it will therefore be seen that the moment of the thread tension about the axis of the warp beam will diminish as the radius diminishes. The design is such that these two diminutions conform so that the thread tension remains constant.

Describing now the transmission gear train coupling the warp beam 1 and the lever 3, the differential gear train 6 in said gear train comprises two bevel gears 7 and 8 rotatable about the axis of the shaft 4 and an intermediate bevel gear 9 in mesh with both gears 7 and 8 and rotatable about an axis at right angles to said shaft 4, said intermediate bevel gear 9 being carried by a casing 10 which encloses the three bevel gears and is itself rotatable about the axis of said shaft 4. The bevel gear 8 is fast with the lever 3, and the bevel gear 7 is fast with a gear 11 which is in mesh with a gear 12 which is in mesh with a gear 13 which is fast with the warp beam 1. This constitutes the transmission train and it will be seen that, assuming that the casing 10 of the differential gear 6 is stationary, clockwise rotation of the warp beam (according to Figures 1 and 2) caused by drawing off thread will cause counterclockwise or upward rotation of the lever 3 against the bias of the weight 5, and clockwise or downward rotation of the lever under the bias of the weight, permitted by the paying back of the thread to the warp beam will cause counterclockwise rotation of the warp beam for taking up the thread.

For adjusting the differential gear train 6 for maintaining the lever at the normal position, the casing 10 of said differential gear train has

integral with it a worm wheel 14 which is in mesh with a worm 15 fast on a worm shaft 16. For returning the lever 3 when it tends to be moved upwardly by the drawing off of the thread from the warp, a sleeve 17 is mounted so as to rotate freely on said worm shaft, and said sleeve carries a pawl 18 which is biased by means of a spring 96 into engagement with a ratchet wheel 19 which is fast on said worm shaft. So long as the loom is running said sleeve 17 and therefore the pawl 18 is oscillated, as will hereinafter appear, about the axis of the worm shaft, and the direction in which the pawl engages the ratchet wheel 19 is such as to rotate said ratchet wheel and therefore the worm shaft 16, the worm 15, the worm wheel 14 and casing 10 of the differential gearing in the direction for rotating the lever 3 in a downward direction. A shield 20, however, is provided, carried by a second sleeve 21 which is also freely rotatable on the worm shaft, and means are provided, as will hereinafter appear, whereby, so long as the lever 3 is within the limits of its normal position, said sleeve 21 occupies a position such that the shield 20 is interposed between the pawl 18 and the ratchet wheel 19. Under these circumstances therefore the pawl 18 oscillates on the surface of the shield 20 without engaging the ratchet wheel 19. But when the lever 3 rises above the limits of its normal position the sleeve 21 is rotated so as to expose the ratchet wheel 19 to the pawl 18, and said ratchet wheel is therefore rotated step by step so as to move the lever down and restore it to its normal position. According to whether the lever 3 is raised a less or a greater distance above the limits of its normal position, the exposure of the ratchet wheel 19 to the pawl 18 is effected to the extent of a less or greater number of teeth, and therefore the steps of rotation of the pawl are smaller or greater and the rate of returning the lever to its normal position is smaller or greater.

For returning the lever 3 when it tends to move downwardly during re-winding of the thread on to the warp, a sleeve 22 is mounted so as to rotate freely on the worm shaft, and said sleeve carries a pawl 23 which is biased by means of a spring 97 into engagement with a ratchet wheel 24 which is fast on said worm shaft. So long as the thread is being paid back to the warp, said sleeve 22, and therefore the pawl 23 is oscillated, as will hereinafter appear, about the axis of the worm shaft and the direction in which said pawl engages said ratchet wheel is such as to rotate said ratchet wheel in the direction for rotating the lever 3 in an upward direction. A shield 25, however, is provided, carried by a sleeve 26 which is also freely rotatable on the worm shaft, and means are provided, as will hereinafter appear, whereby, so long as the lever 3 is within the limits of its normal position, said sleeve 26 occupies a position such that the shield 25 is interposed between the pawl 23 and the ratchet wheel 24, so that no movement is transmitted to the ratchet wheel. When, however, the lever falls below the limits of its normal position the sleeve 26 is rotated so as to expose the ratchet wheel 24 to the pawl 23, and said ratchet wheel is therefore rotated so as to move the lever up and restore it to its normal position. As in the case when the lever is rotated downwardly, the rate of upward rotation varies according to the distance the lever has moved below the limits of its normal position.

For shifting the two sleeves 21 and 26 and their shields 20 and 25, according to the movement

of the lever 3, said lever 3 has an arm 27 rigid with it and projecting downwardly from it at right angles to it and radially with respect to the shaft 4. This arm 27 at its extremity is pivotally connected to one end of an approximately horizontal link 28. The other end of said link is pivotally connected to the upper end of a link 29a whose lower end is pivoted to a fixed point 30a and a second link 28a couples the upper end of said link 29a to the lower end of a link 29 whose upper end is pivoted to a fixed point 30. It will thus be seen that the link 28a can move left or right in a path determined by the links 29 and 29a.

15 Said link 28a at its right hand end is pivoted to the upper end of a link 31 whose lower end is pivoted at 32 to the left hand end of a link 33 whose right hand end is pivoted to a fixed point 34. Said link 28a, at its left hand end is pivoted 20 to the lower end of a link 35 whose upper end is pivoted at 36 to the right hand end of a link 37 whose left hand end is pivoted to a fixed point 38.

The sleeve 21 has a lug 39 projecting from it, and this lug is coupled, by means of a link 40, 25 to the point of connection 32 of the links 31 and 33. The sleeve 26 has a lug 41 projecting from it and this lug is coupled, by means of a link 42 to the point of connection 36 of the links 35 and 37.

30 It will readily be seen that the links are so arranged that, when the lever 3 is moved upwards the link 28 will move to the right. This will cause the point 32; and therefore the link 40 and the lug 39 to move upwards, causing the sleeve 21 and shield 20 to rotate counterclockwise (according to Figure 5). The teeth of the ratchet wheel 19 will therefore be exposed to the pawl 18, and the lever 3 will accordingly be adjusted downwardly and restored to its normal position. 35 During this movement the point 36 and therefore the link 42 and the lug 41 will move only very slightly.

When the lever 3 is moved downwards the link 28 is moved to the left. This causes the point 36 and therefore the link 42 and the lug 41 to be moved downwards, thereby rotating the sleeve 26 and shield 25 clockwise and exposing the teeth of the ratchet wheel 24 to the pawl 23. The lever 3 will accordingly be adjusted upwardly by oscillation of the pawl 23. During this movement the point 32 moves only very slightly.

For causing the sleeve 17 and therefore the pawl 18 to oscillate about the axis of the shaft 16, so long as the loom is in operation, a flange 43 is bolted to a wheel 44. This wheel should be visualized as one of the several wheels which rotate while the loom is in operation. This flange has an eccentric pin 45 mounted on it which is connected to the upper end of a link 46 whose lower end is pivotally connected to one end of a rocking lever 47 which rocks about a fixed shaft 48 between its ends. The other end of said rocking lever is pivotally connected to the lower end of a link 49 whose upper end is pivotally connected to a lug 50 which is integral with said sleeve 17. Therefore as the wheel 44 rotates and the pin 45 moves in the path of a circle, the link 46 moves up and down, and therefore the link 49 moves up and down and the lug 50 together with the sleeve 17 and the pawl 18 oscillate about the axis of the shaft 16.

Before describing the mechanism for causing the sleeve 22 and the pawl 23 to oscillate about the axis of the shaft 16, so long as the thread is being payed back to the warp beam 1, it is neces-

sary to refer briefly to part of the ordinary loom mechanism for taking up the woven cloth 2a. Thus the cloth after weaving is wound on to a roller 51. This is effected by the action of a pawl 52 and ratchet wheel 53, the pawl being connected to a lay sword 54 as will hereinafter appear in such a way that, for each complete reciprocation of the lay sword the pawl makes a complete reciprocation and the ratchet wheel 53 is rotated through one tooth space. The ratchet wheel operates gearing, not shown, which drives a friction roller 55 in engagement with the roller 51 in such a way that said cloth is pulled through and on to said roller 51, an equal length being pulled through at each pick.

To prevent retrograde movement of the ratchet wheel 53, a pawl 56 is provided mounted on one end of a rocking arm 57 which is pivoted at 58 to a fixed point between its ends. This rocking arm 57 is normally positioned so that the pawl 56 engages the teeth of said ratchet wheel, and said pawl is resiliently yieldable relative to said rocking arm so that the ratchet teeth can ride past it but cannot return.

Said rocking arm 57, at its end remote from the pawl 56 is formed so as to provide a second pawl 59, the arrangement being such that said rocking arm 57 and its two pawls 56 and 59 form an escapement device so that, assuming the pawl 52 to be out of engagement with the ratchet wheel, oscillation of said rocking arm about its pivot point 58 will permit the ratchet wheel to rotate in a retrograde manner (i. e. counterclockwise according to Figure 1) to the extent of one tooth for each to-and-fro oscillation of said rocking arm.

When therefore it is wished to pay back some of the thread 2 to the warp beam 1, the loom is stopped and the pawl 52 disengaged from the ratchet wheel, and the rocking arm 57 is oscillated to-and-fro by means of a hand lever 60 to which it is connected as will hereinafter appear, and the warp beam will be free to wind back the thread step-by-step.

To cause the sleeve 22 and pawl 23 to oscillate so long as the thread is being payed back in this way, the hand lever 60 is connected to said sleeve 22 by means of a Bowden cable 61. As will be clear from the drawing said sleeve 22 is formed with a lug 62 which actually carries the pawl 23 and said cable 61 is connected to a point 63 of said lug so that, when said cable is tensioned, that is on movement of the lever 60 to the right for initiating a to-and-fro movement, the sleeve 22 and pawl 23 are moved counterclockwise (according to Figure 4). When the cable 61 is relaxed by return movement of the lever 60 to the left for completing a to-and-fro movement, the sleeve 22 and pawl 23 are permitted to return clockwise under the influence of a tension spring 64 connected between said lug 62 and a fixed point. Thus the pawl 23 is oscillated so long as the threads are being payed back to the warp beam. In this connection reference is made to the previous description explaining how shield 25 is moved according to the position of lever 3 to permit pawl 23 to operate or not.

For lifting the pawl 52 clear of the ratchet wheel 53, a simple over-centre release device is provided, comprising a release lever 65 pivotally mounted between its ends at point x and carrying at one end a pin 66a located underneath but not normally in contact with said pawl 52. The other end of said lever 65 is reduced at 67 and passes through an aperture in the free end of

an arm 68 which rotates about a fixed point 69 and is rigid with an operating handle 70 by which it is adapted to be rotated. A spring 71 coiled on the reduced end 67 of the lever 65 is in compression between the end of the arm 68 and a shoulder on said link 67, and it will be clear from the drawing that an over-centre mechanism is constituted whereby, when the handle 70 is pulled down to the position shown, the lever 65 will snap to the position at which the pin 66a is down as shown and permits the pawl 52 to engage the ratchet wheel 53. When said handle 70 is lifted to the up position, the lever 65 will snap to a position at which the pin 66a is raised and lifts the pawl 52 out of engagement with said ratchet wheel. The upward and downward movements of said lever 65 are limited by a fixed bracket 66.

Describing now the connection between a lay sword 54 and the pawl 52, said pawl 52 is pivotally mounted at 72 to an intermediate point of a lever 73 which is pivotally mounted, at its upper end, at a fixed point 74. Said lever 73 is formed with a longitudinal slot 75 and in this slot a pin 76 engages which is carried by the lay sword 54. Thus as the lay sword is oscillated the lever 73 is oscillated about the point 74, and the pawl 52 is accordingly reciprocated for rotating the ratchet wheel 53.

Describing now the connection between the hand lever 60 and the rocking arm 57 and also the Bowden cable 61, said lever 60 rotates about a fixed point 77 and has rigid with it, and radial with respect to said point 77 a short arm 78. The rocking arm 57 has rigid with it, and radial with respect to the pivot point 58 of said rocking arm a short arm 79. A link 80 connects the extremities of the two arms 78 and 79. It will be clear from the drawing that the arm 78 and the link 80 form a toggle which, when the lever 60 is moved to the right to the position shown in Figure 6, is bent and the arm 79 is lowered and the rocking arm 57 is rotated to the position at which the pawl 59 engages the ratchet wheel 53. When the lever 60 is returned to the left to the position shown in Figure 1, the toggle 78, 80 straightens and lifts the arm 79 and thereby rotates the rocking arm 57 to the position at which the pawl 56 engages the ratchet wheel 53 which is the position used when the loom is weaving.

It will be seen that the Bowden cable 61 is connected to the point of connection of the toggle links 78, 80.

Describing now the means by which the weight 5 is adjusted along the main lever 3 as the radius varies as the thread 2 is being wound or unwound, said weight has small wheels 81 which enable it to run freely along the main lever 3. Actually, the position at which said main lever 3 is maintained is at a slight angle to the horizontal so that said weight 5 tends to run down from the end towards the axis 4 of said lever. Said weight 5 is maintained against thus running towards the axis of said lever by means of a flexible lead 82 which passes from said weight to and round a pulley 83 at the free extremity of said lever; then parallel to said lever to and under a pulley 84 mounted on the shaft 4 about which said lever pivots then to and round a pulley 85, then back and round said pulley 84 and finally to a point of anchorage 86. The pulley 85 and the anchorage point 86 are mounted on an arm 87 which is fast on a rotatable shaft 88 which has on it another arm 89 having at its end a roller 90 which bears on the surface of the reel of thread being unwound or wound on

the warp beam 1, the arrangement being such that, as the radius of the thread diminishes or increases the pulley 85 and anchorage point 86 move so as to permit the weight 5 to run further down the main lever 3, or to draw said weight further up said main lever. The roller 90 which bears on the surface of the reel only exerts a very light pressure which is quite insufficient to cause any entanglement of the thread.

It will have been understood that when the main lever 3 is at a position within its normal limits both the pawls 18 and 23 will be fully maintained out of engagement with their ratchet wheels 19 and 24 by means of the shields 20 and 25 and that in no circumstances can both pawls be permitted to engage their ratchet wheels at the same time. The worm shaft 16 has a handle 91 rigidly mounted on it for enabling it to be rotated at will. This enables the warp beam to be turned by hand when the loom is stopped and is useful when fitting new warps.

Describing now certain constructional details of the apparatus as best shown in Figure 3: for securing the main lever 3 to the bevel gear 8, said lever is bolted to a bracket 92 and said bracket has an integral lug which is formed with a boss 93 which surrounds and is keyed to an elongated sleeve 94 integral with said bevel gear 8. The arm 27 is mounted on this bracket 92 as will be clear from the drawing.

The bevel gear 7 is also formed with an elongated sleeve 95 on which is keyed the gear 11. The casing 10 is rotatably mounted on the two sleeves 94 and 95 as will be clear.

The weight 5 is variable and is made up of pieces which fit into a frame. The degree of weight will vary with different materials and length of the warp, but when the weight is established with a new warp beam it does not require altering until after the warp beam is empty.

The nature of the fixed basic structure on which the parts heretofore described are mounted forms no part of the invention and is deemed to be sufficiently clear from the drawing.

It will have been understood that in ordinary use the thread 2 is continuously drawn off the warp beam. The need for paying the thread back to the warp beam is usually only necessary when faults develop in the woven fabric and this operation usually proceeds for a short space only. During this operation it is desirable that the length of cloth unwound shall be under close control and this is achieved very satisfactorily by the escapement mechanism heretofore described, since this escapement mechanism enables the number of ratchet teeth by which the material is paid back to be counted, if necessary by means of a counting mechanism. Thus the number of picks of weft threads corresponding to the length of fabric unwound, is accurately established and after an equivalent number of weft threads are unpicked, the last remaining weft thread will be correctly disposed to the beating-up motion, and thick or thin places in the fabric will be obviated.

It has been found beneficial to provide anti-friction bearings for the bevel gears 7, 8 and 9, the casing 10, the gear 12 and the warp beam in order to overcome static friction.

What is claimed is:

1. In a warp let-off mechanism, a device for re-winding a limited length of warp on a warp beam at predetermined tension, the said device comprising a given element, biasing means biasing said given element in a given direction, transmission means between said element and

said beam, whereby said biasing means bias said beam to rotate in the direction to wind said thread thereon, and regulating means whereby, in response to said given element moving in said given direction under the influence of said biasing means, and thereby rotating said beam and winding said thread thereon, said transmission means are adjusted in the sense to give said given element a component of movement in the opposite direction, whereby said given element remains substantially stationary despite the continuing rotation of said beam.

2. In a warp let-off mechanism, a device for re-winding a limited length of warp on a warp beam at predetermined tension, the said device comprising a given direction, transmission means between said given element and said beam, whereby said biasing means bias said beam to rotate in the direction for winding said thread thereon, said transmission means comprising a rotatable element adapted, upon rotation, to give said given element a component of movement in the direction opposite to said given direction, a ratchet wheel whose rotation effects rotation of said rotatable element, a pawl for said ratchet wheel adapted to be reciprocated with a constant stroke, and means whereby the distance over which said pawl engages said ratchet wheel at each stroke increases or diminishes as said given element moves in said given direction or returns in the opposite direction, whereby said given element remains substantially stationary despite the continuing rotation of said beam under the influence of said biasing means.

3. In a warp let-off mechanism, a device for re-winding a limited length of warp on a warp beam at predetermined tension, the said device comprising a given direction, transmission means between said given element and said beam, whereby said biasing means bias said beam to rotate in the direction for winding said thread thereon, said transmission means comprising a rotatable element adapted, upon rotation, to give said given element a component of movement in the direction opposite to said given direction, a ratchet wheel whose rotation effects rotation of said rotatable element, a pawl for said ratchet wheel, hand-operated means for reciprocating said pawl continuously with a constant stroke, and means whereby the distance over which said pawl engages said ratchet wheel at each stroke increases or diminishes as said given element moves in said given direction or returns in the opposite direction, whereby said given element remains substantially stationary despite the continuing rotation of said beam under the influence of said biasing means.

4. In a textile machine, a device for alternatively exercising a drag on the rotation of a beam which is rotated by the drawing of a thread therefrom, and thereby maintaining said thread at a given tension, or rotating said beam for winding said thread thereon at a given tension, comprising a given element, biasing means biasing said given element in a given direction, transmission means between said given element and said beam, whereby said biasing means bias said beam to rotate in opposition to the tension of said thread, regulating means whereby, in response to said given element moving in opposition to said biasing means in the direction opposite to said given direction, by the rotation of said beam under the influence of the tension of said thread, said transmission means are adjusted so as to give said given element a com-

ponent of movement in said given direction, whereby said given element remains substantially stationary despite continuing rotation of said beam under the influence of said tension, and regulating means whereby, in response to said given element moving in said given direction under the influence of said biasing means, and thereby rotating said beam in opposition to said tension, said transmission means are adjusted so as to give said given element a component of movement in the direction opposite to said given direction, whereby said given element remains substantially stationary despite continuing rotation of said beam under the influence of said biasing means.

5. In a textile machine, a device for alternatively exercising a drag on the rotation of a beam which is rotated by the drawing of a thread therefrom, and thereby maintaining said thread at a given tension, or rotating said beam for winding said thread thereon at a given tension, comprising a given element, biasing means biasing said given element in a given direction, transmission means between said given element and said beam, whereby said biasing means bias said beam to rotate in opposition to the tension of said thread, said transmission means comprising a rotatable element adapted, upon rotation in one direction, to give said given element a component of movement in said given direction, and, upon rotation in the other direction, to give said given element a component of movement in the direction opposite to said given direction, a first ratchet wheel whose rotation effects rotation of said rotatable element in said one direction, a first pawl for said first ratchet wheel adapted to be reciprocated with a constant stroke, means whereby the distance over which said first pawl engages said first ratchet wheel increases or decreases according as said given element moves in the direction opposite to said given direction or returns in said given direction, whereby said given element remains substantially stationary despite continuing rotation of said beam under the influence of said tension, a second ratchet wheel whose rotation effects rotation of said rotatable element in said other direction, a second pawl for said second ratchet wheel adapted to be reciprocated with a constant stroke, means whereby the distance over which said second pawl engages said second ratchet wheel increases or decreases according as said given element moves in said given direction or returns in the opposite direction, whereby said given element remains substantially stationary despite continuing rotation of said beam, under the influence of said biasing means, in opposition to said tension.

6. In a textile machine, a device for alternatively exercising a drag on the rotation of a beam by the drawing of a thread therefrom, and thereby maintaining said thread at a given tension, or rotating said beam for re-winding said thread thereon at a given tension, comprising a given element, biasing means biasing said given element in a given direction, transmission means between said given element and said beam, whereby said biasing means biases said warp beam to rotate in opposition to the tension of said thread, said transmission means comprising a rotatable element adapted, upon rotation in one direction, to give said given element a component of movement in said given direction, and, upon rotation in the other direction, to give said given element a component of movement in the

direction opposite to said given direction, a first ratchet wheel whose rotation effects rotation of said rotatable element in said one direction, a first pawl for said first ratchet wheel, means driven from the machine mechanism adapted to reciprocate said first pawl with a constant stroke, means whereby the distance over which said first pawl engages said first ratchet wheel increases or decreases according to whether said given element moves in the direction opposite to said given direction or returns in said given direction, whereby said given element remains substantially stationary despite continuing rotation of said beam under the influence of the tension of the thread, a second ratchet wheel whose rotation effects rotation of said rotatable element in said other direction, a second pawl for said second ratchet wheel, hand-operated means whereby said second pawl is adapted to be reciprocated with a constant stroke, means whereby the distance over which said second pawl engages said second ratchet wheel increases or decreases according to whether said given element moves in said given direction or returns in the opposite direction, whereby said given element remains substantially stationary despite continuing rotation of said beam, under the influence of said biasing means, in opposition to the tension of the thread.

7. In a textile machine, a device for exercising a drag on the rotation of a beam by the drawing of a thread therefrom, and thereby maintaining said thread at a given tension, comprising a first gear wheel, biasing means biasing said first gear wheel to rotate in a given direction, a second gear wheel, coaxial with said first gear wheel and adapted to be rotated by rotation of said beam, an intermediate gear wheel in mesh with both said first and second gear wheels, whereby, when the axis of said intermediate gear wheel is stationary, rotation of said beam by the unwinding of said thread therefrom effects rotation of said first gear wheel in the direction opposite to said given direction, and means whereby, in response to such rotation of said first gear wheel, the axis of said intermediate gear wheel is moved around the axis of said first and second gear wheels so as to give said first gear wheel a component of rotation in said given direction, whereby said first gear wheel remains substantially stationary despite the continued rotation of said beam.

8. In a textile machine, a device for exercising a drag on the rotation of a beam by the drawing of a thread therefrom, and thereby maintaining said thread at a given tension, comprising a lever, a weight mounted on said lever and biasing it to rotate about its axis in a given direction, transmission means between said lever and said beam, whereby the tension of said thread is opposed to the bias of said lever and rotation of said beam by the unwinding of said thread gives said lever a component of rotation in the direction opposite to said given direction, regulating means whereby, in response to rotation of said lever in the direction opposite to said given direction, said transmission means are adjusted so as to give said lever a component of rotation in said given direction, whereby said lever remains substantially stationary despite the continued rotation of said beam, and means whereby said weight is adapted to be moved along said lever so as to increase or diminish the leverage according as the diameter of the thread wound on the beam is greater or less, whereby

the tension of the thread is maintained constant.

9. In a textile machine, a device for exercising a drag on the rotation of a beam by the drawing of a thread therefrom, and thereby maintaining said thread at a given tension, comprising a lever, a weight mounted on said lever and biasing it to rotate about its axis in a given direction, transmission means between said lever and said beam, whereby the tension of said thread is opposed to the bias of said lever and rotation of said beam by the unwinding of said thread gives said lever a component of rotation in the direction opposite to said given direction, regulating means whereby, in response to rotation of said lever in the direction opposite to said given direction, said transmission means are adjusted so as to give said lever a component of rotation in said given direction, whereby said lever remains substantially stationary despite the continued rotation of said beam, the position at which said lever remains substantially stationary being a position inclined to the horizontal whereby said weight tends to move by gravity along said lever in one direction, and means whereby said weight is retained against such movement 25 at a limiting position which depends on the di-

ameter of the thread wound on the beam, so that the leverage exercised by said weight varies according to said diameter, whereby the tension of the thread is maintained constant.
